(Cl. D34—15)

To all whom it may concern:

Be it known that we, Herbert P. Fields, and Paul S. Mabie, citizens of the United States, residing at Bellwood, county of Cook, and State of Illinois, and Chicago, county of Cook, and State of Illinois, respectively, have invented a new, original, and ornamental Design for a Tricycle-Mounted Hobbyhorse, of which the following is a specification, reference being had to the accompanying drawings, forming a part thereof, in which:

Fig. 1 is a side elevational view of a tricycle-mounted hobbyhorse, showing our new design;

Fig. 2 is a top plan view thereof;

Fig. 3 is a front elevational view thereof; and

Fig. 4 is a rear elevational view thereof.

The dominant features of the design are shown in full lines.

We claim:

The ornamental design for a tricycle-mounted hobbyhorse, as shown and described.
